Primary Examiner — Terry A Wallace(74) *Attorney, Agent, or Firm* — Craft Chu PLLC;
 Andrew W. Chu(57) **CLAIM**

The ornamental design for a condiment mill, as shown and described.

DESCRIPTION

FIG. 1 is an upper perspective view of the condiment mill showing my design, wherein top and bottom portions are transparent; and,

FIG. 2 is a front elevation view thereof, a back elevation view, a side elevation view, and an opposite side elevation view being identical.

The condiment mill is a handheld device to contain spices and flavorings, such as rock salt and pepper. The bottom portion includes a transparent cover indicated by curved contour lines and an interior portion visible on an outside through the transparent cover.
